TRIGGER CIRCUITS

Robert H. Jenkins, Audubon, N.J., assignor to Radio Corporation of America, a corporation of Delaware
Filed Sept. 15, 1961, Ser. No. 138,400
4 Claims. (Cl. 307—88.5)

This invention relates to trigger circuits and particularly to current-sensitive trigger circuits.

It is an object of the invention to provide an improved transistor trigger circuit which produces a square output pulse even though the input pulse has sloping leading and trailing edges.

It is another object to provide an improved trigger circuit which produces an inverted square output pulse having a duration corresponding with the duration of an input pulse.

It is a further object to provide an improved trigger circuit which produces a square output pulse having a duration corresponding with the time during which the input signal current exceeds a predetermined trigger current "turn-on" threshold and remains greater than a predetermined current "turn-off" threshold.

According to an example of the invention, first and second transistors are cross connected so that the collector of the first transistor is connected to the base of the second transistor, and the collector of the second transistor is connected to the base of the first transistor. The base and collector of the first transistor are connected through respective resistors to respective bias potential terminals. The emitter of the first transistor is connected to another bias potential terminal, and the emitter of the second transistor is connected through an emitter resistor to a bias potential terminal which may be a reference potential terminal. Both transistors are biased to be normally nonconducting. An input signal is applied to the base of the first transistor in a polarity to cause the first transistor to conduct. The voltage at the collector of the first transistor and the base of the second transistor then changes in a direction to cause the second transistor to conduct, whereupon the potential at the collector of the second transistor and the base of the first transistor changes in a direction to make the first transistor conduct to saturation. The values of the bias potentials and the value of the emitter resistor of the second transistor are selected so that the collector current drawn by the second transistor is insufficient to keep the first transistor conducting after the termination of the input signal.

In the drawings:

FIGURE 1 is a circuit diagram of a presently preferred example of a trigger circuit according to the invention;

FIGURES 2a and 2b show a chart of input and output waveforms which will be referred to in describing the operation of the circuit of FIGURE 1;

FIGURE 3 is a circuit diagram of a form of the invention incorporating a unitary semiconductor device in place of two separate transistors; and

FIGURE 4 is a diagram which will be referred to in describing the equivalency of the semiconductor devices in the circuits of FIGURES 1 and 3.

FIGURE 1 shows a trigger circuit including two transistors T₁ and T₂ of opposite conductivity types. The collector of each of the two transistors is connected to the base of the other transistor. In other words, the collector 10 of first, PNP type transistor T₁ is connected to the base 12 of second, NPN type transistor T₂, and the collector 14 of the second transistor T₂ is connected to the base 16 of the first transistor T₁. The base 16 of transistor T₁ is connected through a first resistor R₁ to a first bias potential terminal +E₁. The collector 10 of

2

transistor T₁ is connected through a second resistor R₂ to a second bias potential terminal -E₂. The emitter 18 of transistor T₁ is connected to a third bias potential terminal +E₃. The emitter 20 of transistor T₂ is connected through an emitter resistor R_e to a fourth bias potential terminal or reference potential terminal G. An input terminal 22 is connected through a junction point 23 to the base 16 of transistor T₁. The collector 10 of transistor T₁ is connected to an output terminal 24 and through a clamping diode 26 to a bias potential reference point such as circuit ground.

In the operation of the circuit of FIGURE 1, the transistors T₁ and T₂ are normally biased to be nonconducting. A negative polarity input signal 28 is applied to the input terminal 22 and to the base 16 of transistor T₁. The input signal causes current to flow from the +E₁ terminal through resistor R₁ to the input terminal 22. This flow of current causes a voltage drop to be developed across resistor R₁. When the potential at the base 16 of transistor T₁ falls to a value less than the +E₃ bias potential (+6.5 volts) on the emitter 18, transistor T₁ starts to conduct, allowing current to flow from the +E₃ terminal, through the emitter-collector circuit of transistor T₁ and through collector resistor R₂ to the -E₂ bias terminal. The current through resistor R₂ causes the potential at the collector 10 of transistor T₁ and the base 12 of transistor T₂ to rise (become less negative), which causes the transistor T₂ to be rendered conductive. When transistor T₂ conducts, it draws current in the path from bias terminal +E₁ through resistor R₁, through the collector-emitter circuit of T₂ and through resistor R_e to ground. Transistor T₂ also draws base current from base 16 of transistor T₁. The effect of conduction by transistor T₂ is to further lower the potential at the base 16 of transistor T₁, and to thus cause T₁ to conduct to saturation.

To summarize, once the input signal causes transistor T₁ to start conducting, transistor T₂ provides regenerative feedback which makes transistor T₁ conduct fully and generate the abrupt or vertical leading edge of an inverted output signal 30.

The circuit of FIGURE 1 is a current sensitive trigger circuit. The circuit is triggered when the input current signal 28 causes enough current to be drawn through a first resistor R₁ from bias terminal +E₁ to lower the voltage at base 16 of transistor T₁ a little below the potential of the emitter bias terminal +E₃. Therefore, switching occurs at a time t₁ (FIGURE 2A) when the input signal 28 at input terminal 22 causes the drawing of an amount of "turn-on" current 32 which exceeds the threshold current level 33. This input turn-on current 32 for transistor T₁ has a value slightly more than the value given by the formula

$$\frac{(+E_1) - (+E_3)}{R_1}$$

When transistor T₂ becomes conductive, transistor T₂ draws an additional amount of current 34 into its collector 14. This additional current 34 is drawn from the base 16 of transistor T₁ and also through resistor R₁ from the +E₁ bias terminal. The additional current drawn by transistor T₂ results in transistor T₁ being maintained in a saturated conducting condition. The total current drawn from the junction point 23 due to the presence of the input signal 28 and due to conduction by transistor T₂ is represented by the waveform 36 in FIGURE 2A.

During the trailing edge of the input signal 28, a point is reached at time t₂ where the total current 36 drawn from the junction point 23 to the input terminal 22 and to the transistor T₂ is less than the current threshold value 33 required to keep transistor T₁ conductive. At this time t₂, the conduction through transistor T₁ is reduced, and then the regenerative action of transistor T₂

causes transistor T_1 to be abruptly rendered nonconductive. The inverted output pulse 30 (FIGURE 2b) available at output terminal 24 is thus seen to have abrupt vertical leading and trailing edges occurring at time t_1 and time t_2 , respectively. It is seen that the input current turn-on level at time t_1 is at 33, and the input current turn-off level at time t_2 is at 43.

The positive feedback regenerative current 34 drawn by transistor T_2 is relatively unaffected by transistor characteristics and is accurately determined by the base bias potential (minus the base-emitter drop) divided by the value of emitter resistance. The regenerative collector current drawn by transistor T_2 when transistor T_1 is conductive is thus determined by the value of bias voltage $+E_3$ (less the small internal emitter-collector drop in transistor T_1 and the small internal base-emitter drop of transistor T_2) divided by the value of emitter resistor R_e .

The value of the bias potential $+E_3$ and the value of emitter resistor R_e are selected so that the collector current 34 drawn by transistor T_2 , when transistor T_1 is conductive, is less than the input turn-on current 32. When this rule is followed, the circuit operates as desired in generating an output pulse having a duration corresponding with that duration of the input pulse which exceeds the turn-on level 33 and the turn-off level 43.

On the other hand, an undesired bistable mode of operation obtains when the current drawn by transistor T_2 exceeds the input turn-on current 32 as a result of the employment of a resistor R_e having too small a value. If the collector current of transistor T_2 has a value 40 (rather than the value 34) which is greater than the turn-on current 32, the total current drawn from point 23 is as represented by the dotted waveform 42. It is seen that the dotted waveform 42 does not return to the threshold level 33 after the input pulse 28 has terminated. Therefore, if the emitter resistor R_e has too small a value, the transistors will undesirably remain conductive indefinitely after termination of the input pulse.

For proper operation of the circuit of FIGURE 1 it is important that the input signal 28 be supplied from a current source, rather than a voltage source. A current source is required because the current drawn by the feedback transistor T_2 must be able to change the base-emitter voltage drop of transistor T_1 in order to cause a change in the base current of transistor T_1 . The change in base-emitter voltage drop will not occur if the input signal 28 is supplied from a voltage source, i.e., a source having zero internal impedance. The change in current through resistor R_1 caused by the change in base-emitter drop after transistor T_1 begins conducting should be small by comparison with the current which transistor T_2 is capable of drawing.

Solely by way of example, a circuit according to FIGURE 1 has been successfully operated with circuit elements as follows:

Transistor T_1 -----	2N1300
Transistor T_2 -----	2N585
Resistor R_1 ----- ohms	2700
Resistor R_2 ----- do	4700
Resistor R_e ----- do	4300

FIGURE 3 shows a trigger circuit which is similar to the circuit of FIGURE 1 except in that a unitary semiconductor device 50 replaces the two transistors in the circuit of FIGURE 1, and in that the polarities and conductivity types in the circuit of FIGURE 3 are reversed, with the result that a positive-going input pulse results in a negative-going output pulse. The semiconductor device 50 in the circuit of FIGURE 3 is a four-layer PNPN device having four terminals.

The equivalence of the semiconductor device 50 and the two transistors may be explained with reference to the diagram of FIGURE 4. FIGURE 4 shows two transistors T_1' and T_2' which correspond to the transistors T_1 and T_2 in FIGURE 1 except that they are of reversed

conductivity types compared with the transistors T_1 and T_2 . It is seen in FIGURE 4 that the N-type collector of transistor T_1' is directly connected to the N-type base of transistor T_2' , and that the P-type collector of transistor T_2' is directly connected to the P-type base of the transistor T_1' . The connected N-type regions of the two transistors can be viewed as one N-type region, and the connected P-type regions of the two transistors can be viewed as one P-type region. Therefore, the semiconductor configuration of FIGURE 4 can be simplified to the unitary structure as illustrated by the device 50 of the circuit of FIGURE 4. The semiconductor device 50 effectively constitutes two transistors of opposite conductivity types wherein the collector of each one is common to the base of the other one.

In operation, the circuit of FIGURE 3 is the same as the circuit of FIGURE 1 except that the polarities of the bias sources are reversed and the conductivity types of the semiconductor devices are also reversed, so that the input and output signals are likewise reversed in polarity.

It is thus seen that according to this invention there is provided a simple, economical and effective trigger circuit which is current sensitive, and which is operative to generate a square output pulse upon receipt of an input pulse that may have variously sloping leading and trailing edges.

What is claimed is:

1. A trigger circuit comprising first and second transistors of opposite conductivity types each having base, collector and emitter terminals, means effectively cross connecting the base terminals and collector terminals of said two transistors, bias potential terminals, means including resistors connecting said transistor terminals to said bias potential terminals, said last named means including an emitter resistor connected from the emitter of said second transistor to a bias potential terminal, said transistors being normally nonconductive, means to apply an input signal current to the base of said first transistor which current reaches and exceeds a threshold value at which the first transistor is caused to become conductive, whereby the potential at the collector electrode of the first transistor and the base electrode of the second transistor changes in a direction to cause the second transistor to become conductive, whereupon the potential at the collector electrode of the second transistor and the base electrode of the first transistor changes in a direction to cause the first transistor to conduct to saturation, the values of bias potentials and the value of said emitter resistor being selected so that the collector current drawn by said second transistor is less than said current threshold value and is insufficient to keep said first transistor conducting after the termination of said input signal, and means to derive an output signal from the collector electrode of said first transistor.

2. A trigger circuit comprising a first transistor of one conductivity type having a base connected through a first resistor to a first bias potential terminal, a collector connected through a second resistor to a second bias potential terminal, and an emitter connected to a third bias potential terminal, a second transistor of opposite conductivity type having a base connected to the collector of said first transistor, a collector connected to the base of said first transistor and an emitter connected through an emitter resistor to a fourth bias potential terminal, said transistors being normally biased to be nonconductive, means to apply an input signal current to the base of said first transistor which current reaches and exceeds a turn-on incremental current at a value at which the voltage drop in said first resistor causes said first transistor to become conductive, whereby the potential at the connection between the collector of the first transistor and the base of the second transistor changes in a direction to cause the second transistor to become conductive, whereupon the potential at the connection between the collector of the second transistor and the base of the first transistor

changes in a direction to cause the first transistor to conduct to saturation, the values of potential at said third and fourth bias potential terminals and the value of said emitter resistor being selected so that the collector current drawn by said second transistor is less than said turn-on incremental current, and so that the first transistor turns off when the sum of the input signal current and the collector current of the second transistor falls below said threshold current value, and means to derive an output signal from the collector of said first transistor.

3. A current sensitive trigger circuit comprising first and second transistors of opposite conductivity types each having a base, a collector and an emitter, bias potential terminals, a base resistor connected from the base of the first transistor and the collector of the second transistor to a bias potential terminal, a collector resistor connected from the collector of the first transistor and the base of the second transistor to another bias potential terminal, and an emitter resistor connected from the emitter of the second transistor to a point of reference potential, a connection from the emitter of the first transistor to yet another bias potential terminal, said transistor being normally biased to be nonconductive, means to apply an input signal current to the base of said first transistor to cause it to become conductive, whereby the potential at the collector of the first transistor and the base of the second transistor changes in a direction to cause the second transistor to become conductive, whereupon the potential at the collector of the second transistor and the base of the

first transistor changes in a direction to cause the first transistor to conduct to saturation, the values of potential at said bias potential terminals and the value of said emitter resistor being selected so that the collector current drawn by said second transistor is insufficient to keep said first transistor conducting after the termination of said input signal, and means to derive an output signal from the collector of said first transistor.

4. A trigger circuit as defined in claim 3, and in addition, a clamping diode connected from the collector of said first transistor to a point of reference potential.
